Inventor:
Charles H. Collins
By Ernest D. Jansen, Atty.

UNITED STATES PATENT OFFICE.

CHARLES H. COLLINS, OF COLONIE, NEW YORK.

AXMINSTER LOOM.

Application filed May 25, 1921. Serial No. 472,437.

To all whom it may concern:

Be it known that I, CHARLES H. COLLINS, a citizen of the United States of America, residing at the village of Colonie, in the 5 county of Albany and State of New York, have invented certain new and useful Improvements in Axminster Looms, of which the following is a specification.

My present invention relates to looms for 10 weaving Axminster carpets and rugs and the object of my invention is to so improve the construction of such looms, that when in operative condition they will at all times turn off a more nearly perfect product. 15 Other objects being to simplify the construction and adjustment of such looms; to reduce the cost of upkeep by doing away with the necessity of frequent adjustment of the operating cams; and to increase production by making it feasible to operate the 20 looms at a higher rate of speed.

The improvements herein illustrated and described are applicable to looms of the types illustrated and described in patents to 25 Skinner—288,266—Nov. 13, 1883, Tymeson—571,418—Nov. 17, 1896, Clark—732,518—June 30, 1903, and consists broadly in providing a secondary cam shaft adapted to carry a part of the cams or other motion 30 imparting means which in the present type of looms are all carried on the main driving shaft; in driving the main shaft at a much higher speed than such shafts are driven in present type looms; and in driving the secondary cam shaft at a slower fixed speed 35 relative to the speed of said main shaft. (Said speed ratio depending on whether the machine is a "two" "three" or "four shot" loom).

40 I prefer to drive the secondary cam shaft from the main shaft by means of gears of suitable ratio, but I do not wish to limit myself to this means as any type of drive from any point or points which will cause the desired relative speed will answer my purpose.

45 As virtually all the present type looms used in the production of Axminster carpets and rugs are of the "three shot" type I shall confine my description and comparisons to 50 looms of that type.

In the present types of looms where all of the cams and motion imparting mechanisms are carried on the main or driving shaft, it

is necessary to use "three point" cams to impart motion to the mechanisms which operate the selvage shuttle, lay, weft tension, and let off; and a three segment interrupted gear or a three point cam to drive the weft needle mechanism. Each of the foregoing being required to operate three times with 60 each revolution of the main shaft.

It is also necessary for one of the high points on the "lay" cam to have a longer bearing surface in order to provide the necessary dwell of the lay at the time when the 65 pile yarns are being drawn from the spools, just before the yarns are cut to their proper length.

When the loom is in operation the time of this dwell is practically taken or transferred from the other two high points, and it is impossible to have the high points on this cam equally spaced on the circle if all high points are same shape, and have the lay motions synchronize with the other motions in order to weave the desired fabric. 75

One particular motion which would fail to synchronize with the lay motion, would be the needle motion which would be much 80 too early for the lay.

I have divided the time on the old type of needle motion by removing some of the teeth from the interrupted gear and making one tooth less on the pinion; these changes cause the needle to dwell longer when at rest 85 on the interrupted space and travel faster when in motion. This arrangement of the needle motion gives the proper timing when lay cams are spaced equi-distant about the main shaft.

90 This makes the working points on the needle motion also equi-distant. It is therefore clearly seen that all cams pertaining to the lay, weft needle, weft tension, and selvage shuttle, etc., can be spaced equi-distant about the main shaft.

95 The unequal surfaces of the high points on the usual lay cam are also a disadvantage on account of the resultant uneven wear which is one cause of poor work. The 100 shorter high points on the lay cam wear much faster than the longer one, and when they are worn the throw of the lay is shortened and the lay does not place the weft in proper position when operated by the worn 105 high points. Consequently the broad high

point is called upon to push up all three shots. This it may fail to do, and as a consequence of such failure the tuft turning comb will "poke" often producing what is termed "dirty back." After the weft tuft holding shot is inserted the comb is supposed to push the end of the tuft yarn around said shot and up between the cotton warps. If the tuft holding shot has not been beaten up to its proper position by the lay, the comb is apt to catch on the misplaced shot and fail to turn the ends of the tuft yarns up properly. This "poking" is one cause of imperfect work as those skilled in the art will readily understand.

The shuttle cams must be exactly alike and timed with the utmost exactness to the needle motion in order to make a close and uniform selvage. A poor selvage will be the result if the shape and time is not exact and the product will be classed as imperfect or "seconds."

The knife or cutting motions, the clutch and tuft frame carrying motions, the chain or spool carrying motion, the comb or tuft turning motion, and the shed or heddle motion all operate but once with each revolution of the main shaft hence the cams which impart motion to these mechanisms have but one high point.

By placing the cams equi-distant on their respective circles it is necessary to change the time of the frame-carrying cam by dividing the time on same so it will travel a little slower at one point and a little faster at another, in order to give the lay time to get out of the way of the frame lowering clutches.

In order to overcome the many disadvantages of the three cams on one circle (three point cams), to make a better quality fabric, do away with expensive three-point cams thus reducing the cost of construction; I cause the main shaft to run at triple the speed of such shafts on present types of looms, and instead of using three point cams I use only one point cams. This makes much less work for the loom fixer as he has only one adjustment to make, where on the old type looms he had three—one on each side of the different motions.

As the main shaft makes only about 8 R. P. M. on a present type of wide Axminster loom it is obvious that where the looms are run by high speed motors (as in most mills) it is necessary to gear down to obtain the required speed.

On account of the slow speed of the main shaft it is hard to get quick motions on some of the cams where quick motions are much to be desired.

By running the main shaft at three times the speed at which they are run in the old types of looms, much better shaped cams can be used as the angles can be reduced

about two-thirds and still impart the required motion. See cam 7, in Fig. 1.

In the old type looms some of the angles are so acute that the ball or roller will almost lock with the cam points, which makes it very hard on the loom.

In my improved loom I run the main shaft at three times the speed of the main shaft in old types of looms, and use "one point" cams to impart the necessary motion to the selvage shuttle, lay, weft tension, and let off mechanisms; and a one segment interrupted gear, or a one point cam, to drive the weft needle mechanism. The cams and gear for operating these mechanisms being the only ones mounted on the main shaft of my improved loom.

Adjacent to and parallel with the main shaft I mount a secondary shaft adapted to carry the cams which impart motion to the tuft cutting mechanism; the frame clutch, frame carrying, and frame lowering mechanisms; the comb or tuft turning, and the shed or heddle mechanisms. This secondary shaft is driven at one-third the speed of the main shaft, and on it is also carried the usual chain cam, the function of which is to advance the frame carrying chains one space with each revolution of said shaft.

The accompanying drawings illustrate the new features of my improved loom.

In the drawings Fig. 1 is a partial side elevation of my improved loom. Fig. 2 is a plan of my improved needle cam. Fig. 3 illustrates my improved needle motion gear set, in which 13 is the interrupted gear upon axle 3 meshing with spur gear 15 on axle 16. This gear is a substitute for the one point cam of Fig. 2. Fig. 4 is a plan view showing diagrammatically the main and secondary shafts and the cams, etc., which are mounted on each.

Referring to the drawings, Fig. 1, 2 represents a side frame of my improved loom, 3 the main shaft on which is fastened in any suitable manner the pinion 4, meshing with and adapted to drive the gear 5 fastened on the secondary shaft 6. 7 represents one of the various motion imparting cams which are mounted on the main shaft 3, and adapted to actuate the selvage shuttle, lay, weft tension, and let off mechanisms of the loom.

On the proportionately slower turning secondary shaft 6, are to be mounted the usual cams adapted to actuate the tuft cutting mechanism; the frame clutch, frame carrying and lowering mechanism; and the comb and heddle mechanisms.

On a loom constructed in accordance with my invention greater production is obtained on account of the higher speed at which it may be safely operated. The expense of construction is reduced. The life of the

cams materially lengthened on account of their improved shape which permits of the hard long wearing scale being left on the castings. This loom also requires much less attention on the part of the loom fixer, and can be adjusted properly by a less skilled workman, if necessary; it will also produce a closer and more uniform selvage and the product as a whole will be more nearly perfect as "dirty back" which is caused by failure of the comb to properly turn up the ends of the tuft yarns will be an exceptional happening.

What I claim is new and desire to secure by Letters Patent is:

1. In an Axminster loom of the type utilizing a tube frame for inserting the tuft yarns between the warp, and a comb for turning the free ends of the tuft yarns around the tuft holding shot, the combination of: a main shaft having mounted thereon means for actuating the weft needle mechanism one cycle during each revolution thereof, a plurality of cams each adapted to actuate a part of the loom mechanism during each revolution of said main shaft, one to actuate the lay mechanism, one the selvage shuttle mechanism, and one the weft tension mechanism; and a second shaft parallel to and driven at a proportionately slower speed than said main shaft and having mounted thereon a plurality of cams each adapted to actuate a part of the loom mechanism during each revolution thereof, one to actuate the tuft cutting mechanism, one the frame carrying mechanism, one the clutch mechanism, one the comb or tuft turning mechanism, and one for each shed or heddle mechanism.
2. In an Axminster loom of the type utilizing a tube frame for inserting the tuft yarns between the warp, and a comb for turning the free ends of the tuft yarns around the tuft holding shot, the combination of: a main shaft having mounted thereon a one segment interrupted gear adapted to actuate the weft needle mechanism one cycle during each revolution thereof, and a plurality of cams each adapted to actuate a part of the loom mechanism during each revolution of said main shaft, one to actuate the lay mechanism, one the selvage shuttle mechanism, and one the weft tension mechanism; and a second shaft parallel to and driven at a proportionately slower speed than said main shaft and having mounted thereon a plurality of cams each adapted to actuate a part of the loom mechanism during each revolution of said second shaft, one to actuate the tuft cutting mechanism, one the frame carrying mechanism, one the clutch mechanism, one the comb or tuft turning mechanism, and one for each shed or heddle mechanism.
3. In an Axminster loom of the type utilizing a tube frame for inserting the tuft yarns between the warp, and a comb for turning the free ends of the tuft yarns around the tuft holding shot, the combination of: a main shaft having mounted thereon a plurality of cams each adapted to insert the tuft yarns between the warps, and a comb for turning the free ends of the tuft yarns around the weft shots, the combination of: a main shaft having mounted thereon a one segment interrupted gear adapted to actuate the weft needle mechanism, and a plurality of cams each adapted to actuate a part of the loom mechanism during each revolution of said main shaft, one to actuate the lay mechanism, one the selvage shuttle mechanism, and one the weft tension mechanism; and a second shaft parallel to and driven at a proportionately slower speed than said main shaft and having mounted thereon a plurality of cams each adapted to actuate a part of the loom mechanism during each revolution thereof, one to actuate the tuft cutting mechanism, one the frame carrying mechanism, one the clutch mechanism, one the comb or tuft turning mechanism, and one for each shed or heddle mechanism.
4. In an Axminster loom of the type utilizing a tube frame for inserting the tuft yarns between the warp yarns and a comb to turn the free ends of the tuft yarns around the weft or tuft holding shot, the combination of a main shaft having mounted thereon means for actuating the weft needle mechanism one cycle during each revolution thereof, and a cam having but one high point adapted to actuate the lay mechanism, and a plurality of cams each adapted to actuate a different part of the loom mechanism; a second shaft parallel to said main shaft and having mounted thereon cams adapted to actuate other parts of the loom mechanism; and means for driving one of said shafts from the other.
5. In an Axminster loom of the type utilizing a tube frame for inserting the tuft yarns between the warp yarns and a comb for turning the free ends of the tuft yarns around the weft or tuft holding shot, the combination of a main shaft having mounted thereon a cam having but one high point and adapted to actuate the selvage shuttle mechanism, and a plurality of cams each adapted to actuate a different part of the loom mechanism; a second shaft parallel to said main shaft and also having mounted thereon a plurality of cams adapted to actuate other parts of the loom mechanism; and means for driving said second shaft at a speed proportionately slower than that of said main shaft.
6. In an Axminster loom of the type utilizing a tube frame for inserting the tuft yarns between the warp yarns and a comb for turning the free ends of the tuft yarns around the weft or tuft holding shot, the combination of a main shaft having mounted

ed thereon a cam having but one high point and adapted to actuate the weft tension mechanism, and a plurality of cams each adapted to actuate a different part of the loom mechanism; a second shaft parallel to said main shaft and also having mounted thereon a plurality of cams

adapted to actuate other parts of the loom mechanism; and means for driving said second shaft at a speed proportionately 10 slower than that of said main shaft.

In testimony whereof I have affixed my signature.

CHARLES H. COLLINS.
